UNITED STATES PATENT OFFICE.

CHARLES H. NICKELL, OF MONTROSE, COLORADO.

BOTTLE-TAP.

1,324,206.

Specification of Letters Patent.

Patented Dec. 9, 1919.

Application filed April 2, 1919. Serial No. 286,899.

To all whom it may concern:

Be it known that I, CHARLES H. NICKELL, a citizen of the United States, residing at Montrose, in the county of Montrose and State of Colorado, have invented certain new and useful Improvements in Bottle-Taps, of which the following is a specification, reference being had to the accompanying drawings.

10 This invention relates to devices for withdrawing liquids from bottles without the necessity of removing the cap or other closure from the bottle, and particularly to devices of that character wherein there is a tubular puncturing device which is forced through the bottle cap or cork without removing the cork or cap, the puncturing device being provided with a tap or valve for controlling the discharge of liquid from the 15 container.

The general object of my invention is to provide an improved tap particularly adapted for use with bottles containing effervescent liquids, such as ginger ale, mineral water, champagne, etc., including a clamp designed to be placed over the mouth of the bottle and engaged therewith, this clamp having the general form of a cap and being provided with a rubber or other gasket, and said cap and gasket being provided with a central passage through which the tubular puncturing device may be inserted.

A further object is to provide a device of this character embodying a cap designed to be placed over the mouth of the bottle and the regular cap thereon, and having a plurality of segmental clamps swingingly connected to the false cap and having inwardly turned flanges at their upper ends adapted 40 to grip beneath a bead or flange on the bottle neck or mouth and provide means whereby these clamps may be urged inward into clamping engagement with the bottle.

Still another object is to provide a false cap with an interiorly disposed, centrally perforated, rubber gasket with clamping levers having shanks extending into the cap through slots in the side wall of the cap, and provide a guide member slidingly mounted 45 in the top of the false cap and engaged with the shanks of the clamping members so that when the guiding member is forced downward, the angular ends of the clamping members will be forced outward to permit 50 the false cap to be placed upon the bottle top, so that when pressure is relieved, the

rubber gasket, acting as a spring, will force the guiding member upward and thus urge the clamping members into engagement with the bottle.

Other objects have to do with the details of construction and arrangement of parts, as will hereafter more fully appear.

My invention is illustrated in the accompanying drawings, wherein:

Fig. 1 is a vertical sectional view of one form of my bottle tap;

Fig. 2 is a sectional view of the cap portion of the device with the jaws opened;

Fig. 3 is a side elevation of the upper portion of the bottle with my tap thereon;

Fig. 4 is a vertical sectional view of a modified form of my device;

Fig. 5 is a section on the line 5—5 of Fig. 4;

Fig. 6 is a side elevation of the tap in applied position;

Fig. 7 is a vertical sectional view through the cap portion;

Fig. 8 is a vertical sectional view of the tap showing the outlet valve retracted; and

Fig. 9 is an under side plan view of the gasket.

In the accompanying drawings, I have illustrated two forms of my invention. In 85 the construction illustrated in Figs. 1 to 3 there is a cap designated 10 which is adapted to fit over the top or mouth of a bottle and which is provided with the inwardly projecting annular flange 11 at its upper end. 90 This flange also projects slightly outward beyond the wall of the cap. Disposed between the top and bottom of my cap is an inwardly extending diaphragm 12 having a central opening 13 and mounted upon the 95 cap at diametrically opposite portions thereof are the clamping jaws 14, each clamping jaw being arcuate in section, angularly bent at its lower edge, as at 15, and reduced in width toward its upper end to form a shank, 100 the upper end of the shank being bent to form a hook 16 inserted through a perforation in the side wall of the cap. Disposed to engage and wedge down over the shanks of the jaws is a ring 17, and disposed within 105 the cap between the bottom thereof and the web or diaphragm 12 is a gasket 18 of rubber, leather, composition, or any other suitable material, this gasket having a central opening coinciding with the opening 13 and 110 being preferably recessed at its center, as at 19. It will be obvious that when this cap is

placed upon the mouth of a bottle, it is to be forced down until the gasket is compressed and then the ring 17 forced downward so as to force the jaws inward and the flanges 15 of the jaws beneath the usual bead or rim flange on the top of the bottle, thus locking the cap securely in place.

Coacting with the cap is a closure perforator and valve which comprises a valve casing 20, closed by a screw-threaded plug 21 at its lower end, this plug being hollow, and having extending from it a perforating tube 22 formed at its lower end with a pointed extremity and provided adjacent its lower end with an inlet opening 23. Midway of the valve casing 20 there is provided the web 24 having a central opening formed to provide a valve seat, and coacting with this opening is a valve 25 having a stem 26 extending upward into the upper portion of the valve and acted upon by a lever 27 operatively engaged with the valve casing so that when the exterior portion of the lever 27 is depressed, the stem 26 will be depressed, opening the valve against the force of a spring 28. The valve casing above the septum or web 21 is provided with the discharge nozzle 29.

It will be seen that the valve casing with its tubular portion 22 constitutes a combined tap and perforator and after the cap 10 has been put in place upon the bottle, this pointed perforator 22 is forced downward through the central opening in the cap and forced through the metallic cap or closure ordinarily used on ginger ale, soda pop, and other bottles containing effervescent liquids. So long as the valve 25 remains closed, and this valve is held to its seat not only by the spring 28 but by the pressure of the gas within the lower portion of the valve casing, no liquid will be discharged, but, of course, when the valve is open, the liquid will be discharged through the perforating tube 22 out through the discharge nozzle or mouth 29. By means of this device it is an easy matter to discharge only a portion of the contents of a bottle containing effervescent liquids and retain the remainder of liquid within the bottle without the gas escaping therefrom which, of course, is not the case where the cap of the bottle or other closure of the bottle is removed.

In Figs. 4 to 9 I show another and preferable form of my device. In this construction, I provide a cap 30 which is also made of metal, the cap being provided with a central opening 31. Adjacent the top of the cap, the cap is slotted at a plurality of points 60 for the reception of the upper angularly bent ends of the shanks 32 of clamps 33. Each of these clamps is arcuate in form at its lower end, and is angularly bent at its lower edge, as at 34, to extend beneath the bead *a* of a bottle A. Disposed through the opening 31

is a relatively short, tubular member 35 flanged at its lower end, as at 36, and preferably, though not necessarily, this flange is so formed as to loosely receive the inner ends of the shanks 32 of the clamps. Thus 70 when this member 35 is forced inward, it will tend to shift the lower ends of the clamps outward. When the member 35 is forced upward, it will tend to urge the lower ends of the clamps inward. 75

Disposed within the cap is a rubber or other elastic gasket 37 having preferably its under face hollowed out, as at 38, and having a relatively smaller opening 39 on its under face. In alignment with this opening 39 80 there is a relatively small opening 40 through which the liquid is discharged from the cap into the tubular member 35 and so into the tap. This gasket is put in place within the cap and normally bears against the flanged, 85 inner end of the tubular member 35 so that the elasticity of the gasket tends to push the tubular member upward and tends to urge the clamping terminals of the clamps 33 inward. If, however, the member 35 is 90 forced inward against the resiliency of the gasket, the lower ends of the clamps will be forced outward in the manner heretofore described.

The tap and perforator comprises a valve 95 casing 41 and a tubular pointed perforator 42 which, in this instance, extends at right angles to the valve casing, this tubular perforator being provided with the inlet opening 43. The valve casing is tubular and has 10 a relatively small nozzle 44 formed at its inner end to provide a valve seat 45 and the opposite end of the casing 41 is closed by a screw-threaded plug 46 through which passes a valve stem 47 carrying at its extremity a valve 48.

While I do not wish to be limited to this feature, yet preferably there will be a rubber sleeve 49 surrounding the valve stem, this sleeve bearing at one end against the 11 valve 48 and at its opposite end being expanded to fit around the reduced inner end of the plug 46. This rubber sleeve, inasmuch as it fits around and over this reduced inner end of the plug 46, prevents gas 11 from escaping around the stem at this point and also performs the further function of a spring acting to urge the valve to a closed position. Upon the extremity of the valve stem is provided an operating lever 50 12 which, when its outer end is forced inward, fulcrums against the extremity of the valve 46 so as to draw the valve from the valve seat. When this operating lever is released, the elasticity of the sleeve 49 will cause the 12 valve to close. This construction operates in nearly the same manner as the one previously described.

When it is desired to use the device, the perforator is withdrawn from the central 13

opening of the tubular portion 35 and then the cap 20 is disposed over the mouth of the bottle, the closure of the bottle, of course, remaining in place. As soon as pressure is relieved on the member 35, the resilience of the hollow gasket will act to urge the clamps inward around the bottle neck and beneath the bead *a* and then the perforator is forced downward through the opening 10 in the member 35 and the sharp point of the perforator through the bottle cap, cork, or other closure. Then the liquid can be withdrawn from time to time as required without allowing the escaping of an undue 15 quantity of gas.

The practical nature of my invention will be understood by all who handle bottles containing effervescent liquids. Ginger ale, ginger pop, mineral waters, soda pop, etc., 20 are often put up in bottles that hold six to ten glasses and contain gas under a pressure of from fifty to sixty pounds. Now when a dealer sells a single glass, he opens the bottle, draws off a glassful therefrom, 25 and then sets the bottle away, but even though he corks the bottle up tightly, a very large quantity of the gas has escaped so that the pressure is very greatly reduced, and even though he corks it up securely and 30 tightly there will be a more or less constant escape of gas from the bottle so that even where the bottle is immediately corked, the last two or three glasses of the liquid are flat and vapid. With my device, the bottle 35 stopper, seal, or closure is not removed, but perforated by the perforator and the gas is prevented from escaping around the perforator by the gasket which has been clamped down tightly over the bottle closure, 40 and which, being rubber, fits against the closure tightly and fits the perforator very snugly. The steel point of the perforator, which is preferably made in a separate piece inserted into the tubular perforator itself, 45 which may be made of softer metal, may be driven in and through the metallic cap usually found on bottles of this character even by a tap of the hand or by driving the top of the perforator upward against a 50 counter. The contact of the top of the bottle with the washer creates an air tight connection and the liquid is then drained off through the faucet or tap in an obvious manner. The contents of the bottle having 55 all been poured out or discharged, then the perforator and cap is removed and the clamps disengaged from the bottle, either by pulling upward on the ring 17 in Fig. 1 or by forcing downward on the central 60 tubular member 35, as in Fig. 7.

While I have illustrated two forms of my invention which I believe to be particularly effective in practice, which may be cheaply made, and which may be readily 65 kept clean, yet it will be understood that

the constructions may be varied as regards details in many ways without departing from the spirit of the invention, the drawings being merely illustrative of two embodiments of the invention and the device 70 being capable of embodiment in many different forms.

I claim:—

1. A device of the character described comprising a metallic cap adapted to be disposed over the top of a bottle and having a plurality of slots in its periphery extending parallel to the top of the cap, a plurality of transversely arcuate clamping members formed with shanks angularly bent 75 to extend through said slots and having rocking engagement with the wall thereof, the free ends of the clamps being flanged to engage beneath the bead at the top of a bottle neck, means for urging the angular 80 ends of the clamps inward, an annular, perforated gasket disposed within the cap and adapted to fit against the bottle top, and a combined tap and perforator comprising a valve casing, and a tubular perforator 85 extending from the valve casing and communicating with the interior thereof and having a pointed, perforated extremity.

2. A device of the character described comprising a cap adapted to be disposed over a bottle top and slotted at a plurality of points in its side wall, the top of the cap having a central opening, an annular gasket disposed within the cap, a plurality of clamping members, each formed with a 90 shank, the shank being bent at its upper end and passing through one of said slots whereby the clamping members are swingingly engaged with the cap, means whereby 95 said clamping members may be forced inward to engage the bead on the bottle neck, a combined tap and perforator comprising a valve casing, a pointed tube extending from the valve casing and adapted to be forced through the central opening in the 100 cap and gasket and through a bottle top, the perforator having an inlet opening adjacent its extremity, and a valve controlling 105 the discharge of liquid from the valve 110 casing.

3. A device of the character described comprising a cap adapted to fit over a bottle top and having a central opening in its top, a tubular member shiftably mounted in said opening, a plurality of bottle clamps 115 swingingly mounted upon the cap and having portions operatively engaged by said tubular member whereby a movement of the tubular member in one direction will shift the clamps outward and a movement in the 120 opposite direction will shift the clamps inward, each of said clamps having a bead engaging flange at its free end, an annular gasket disposed within the cap and bearing 125 against the tubular member, a tap and per-

- forator comprising a valve casing, a pointed tube extending therefrom and having an inlet opening, and a valve in the valve casing controlling discharge therefrom.
- 5 4. A device of the character described comprising a cap adapted to fit over a bottle top and having a central opening in its top, a tubular member shiftably mounted in said opening, a plurality of bottle clamps 10 each having a shank, the upper end of the shank of each clamp being angularly bent and inserted through a slot in the side wall of the cap and then extending beneath the top of the cap, an elastic gasket disposed within 15 the cap and bearing against said shanks and when under pressure forcing the shanks against the top of the cap and the free ends of the clamping members inward, a tap and perforator comprising a valve casing, and 20 a tubular pointed member extending therefrom and having an inlet opening and adapted to be inserted through the cap and gasket and through a bottle top.
5. A device of the character described 25 comprising a cap having a central opening in its top, a plurality of clamping members, each arcuate in cross section, and having a

shank angularly bent, the cap being formed in its side wall with slots through which the shanks are inserted, the shanks normally lying parallel to the top of the cap, the free ends of the shanks being angularly bent to engage beneath the bead of a bottle neck, a tubular member disposed through the opening of the cap and bearing against the shanks, an elastic gasket disposed within the cap and bearing against the opposite faces of the shanks whereby when the gasket is compressed by engagement with the bottle top to force the shanks against the top of the cap and the flanged ends of the shanks against a bottle, a combined tap and perforator comprising a valve casing, a perforating tube having a pointed extremity formed with an inlet opening, the perforator being adapted to be forced through the tubular member on the cap, through the gasket, and through the bottle top.

In testimony whereof I hereunto affix my signature in the presence of two witnesses. 50
